UNITED STATES PATENT OFFICE.

JULIUS W. CRIGLER, OF BLOOMINGTON, ILLINOIS.

HANGER FOR SHADE-ROLLERS.

SPECIFICATION forming part of Letters Patent No. 576,951, dated February 9, 1897.

Application filed August 3, 1896. Serial No. 601,521. (No model.)

To all whom it may concern:

Be it known that I, JULIUS W. CRIGLER, a citizen of the United States, and a resident of Bloomington, in the county of McLean and State of Illinois, have invented certain new and useful Improvements in Hangers for Shade-Rollers; and I do hereby declare that the following is a full, clear, and exact description of the invention, which will enable others skilled in the art to which it appertains to make and use the same, reference being had to the accompanying drawings, which form a part of this specification.

My invention relates to hangers for shade-rollers which are secured to the upper sash of a window so as to move therewith, so that when the sash is lowered the shade may be let down and yet not interfere with the free ventilation of the room.

The object of the invention is to provide an improved construction of shade-hanger which shall possess superior advantages with respect to efficiency in use.

The invention consists in the novel construction and combination of parts herein-after fully described and claimed.

In the accompanying drawings, Figure 1 is a perspective view of the upper part of the upper sash, showing my improvements applied thereto. Fig. 2 is a similar view looking from the rear. Figs. 3 and 4 are detail sectional views.

In the said drawings the reference-numeral 1 designates the upper rail of the upper sash of a window, to which is secured near each end a bracket 2, bent at right angles, forming a vertical portion 3, which is secured to said rail, and an outwardly-extending horizontal portion 4, which engages with the inwardly-turned flanges 5 of the horizontal portion 6 of an angular extensible bracket 7. In the upper ends of the vertical portions 6 of these brackets are made two parallel slits forming three arms, a central one 7^a and two end arms 8. The said central arm 7^a is formed with a shoulder or bent at its junction with the portion 6, so that it will be in a different plane from the side or end arms 8, so that a hanger-bar, hereinafter described, may be passed therebetween. The extremities of the said arms are bent inwardly and downwardly, forming lugs which engage with the upper

edges of the hanger-bars, and the central arms 7^a are provided on the inner sides with a projection 9.

The numeral 10 designates the hanger-bars, having their ends bent outwardly at right angles and formed, respectively, with the usual slot and hole to receive the journals of the shade-rollers. One of these bars at its inner end is formed with inwardly-turned flanges 12, forming guideways within which the inner end of the other bar works, and said bars are formed on their rear sides with depressions 13, coinciding with the projections on 55 the arms 7^a.

The manner of using the device will be readily understood. The brackets 2 are secured to the upper rail of the sash near the ends thereof and the brackets 6 adjusted by sliding them in or out, so that the shade when the sash is lowered will pass by the lower sash. The hanger-bars are then passed between the central and side arms at the upper ends of the bracket 6 and adjusted laterally to accommodate them to the length of the shade-roller by sliding them in or out upon each other, the projections in the central arms 7^a engaging with the depressions 13, so that they will be securely held in their adjusted positions, yet the resiliency of the arms allowing the projections to be disengaged from the depressions to allow the bars to slide in and out.

A shade-hanger constructed as above described can be produced very economically, 85 as the parts can be stamped out of sheet metal, and by securing them to the upper sash the shades will move therewith when the sash is lowered. By this means the window can be opened at the top, allowing a free entrance 90 of air, while the shade can be drawn or lowered without any liability of the latter being broken or injured by the wind, as is the case in the ordinary shades when lowered and the upper sash opened.

While I prefer to make the device of sheet metal on account of economy it may be cast or otherwise produced or made of wood, if desired.

Having thus described my invention, what 100 I claim is—

1. In a shade-hanger, the combination with the angular brackets adapted to be secured to a window-sash, of the extensible angular

brackets connected therewith, the three vertical arms at the upper ends thereof, the central one of which is formed with a bend, so that it will be in a different plane from the other two, and the ends of said arms being bent or curved inwardly forming ways, and the overlapping adjustable hanger-bars, seated in said ways, substantially as described.

2. In a shade-hanger, the combination with the angular brackets adapted to be secured to a window-sash, of the angular extensible brackets having inwardly-turned flanges engaging therewith, the arms in different planes at the upper ends of said extensible brackets,

and one of said arms of each bracket formed with a projection, the overlapping adjustable hanger-bars, having depressions coinciding with said projections and one of said bars formed with flanges overlapping the other bar, substantially as described.

In testimony that I claim the foregoing as my own I have hereunto affixed my signature in presence of two witnesses.

JULIUS W. CRIGLER.
